UNITED STATES PATENT OFFICE.

FREDERICK DIEHL, OF ELIZABETH, NEW JERSEY, ASSIGNOR TO THE SINGER MANUFACTURING COMPANY, OF ELIZABETH, NEW JERSEY, A CORPORATION OF NEW JERSEY.

ELECTRIC SEWING-MACHINE OUTFIT.

Application filed October 8, 1925. Serial No. 61,170.

This invention relates to motor driven sewing machines such as are customarily stationed for use on a specially constructed sewing machine table having a top which is usually apertured for reception of the sewing machine.

The present day demand is for a table which, although specially constructed for the support and operation of a sewing machine, has the neat and graceful appearance of a library table when not in use, with nothing conspicuous to suggest its relation to machinery.

Outfits of this character commonly comprise a table, a sewing machine, a motor for driving the sewing machine, and a foot- or knee-operated device for controlling the speed of the motor; many users preferring a foot-controlled outfit. In the case of the foot-controlled outfit, however, as heretofore constructed, the foot-controller is a pedal-operated rheostat which is mechanically detached from the remainder of the outfit; being merely connected electrically in the motor circuit.

When the sewing machine is not in use it is customarily lowered into the housing cavity of the table, below the table top, while the controller and cord must be disconnected from the motor circuit, the cord coiled up, and the controller and cord, which make rather a bulky and troublesome package, stored away, usually in a cupboard drawer or on a closet shelf. When preparing the machine for use, the controller is placed upon the floor and the cord uncoiled and connected in the motor circuit. With foot-controlled outfits of this type there is a tendency of the controller to creep over the floor and a possibility of its being accidentally overturned. Due to the fact that the controller occupies no fixed position on the floor, relative to the table, it is necessary for the operator to peer under the table to find the controller before placing the foot on the pedal.

The primary object of the present improvement is to provide a foot-controlled electric sewing machine outfit of the library table type retaining the advantages of neatness of appearance and lack of suggestion of machine use when closed, and eliminating the above referred to disadvantages of prior foot-controlled sewing machine outfits.

Other objects of the invention will in part be obvious and in part be hereinafter more fully described.

To the attainment of the ends in view a sewing machine table, preferably of the four-legged type having no cross braces or tie rods between the legs, has a pedal element detachably connected to the lower end of one of its legs, which latter is preferably of hollow or longitudinally channelled construction to receive and conceal an operative connection extended upwardly from the pedal to a motor speed-controlling element or rheostat stationed near the upper end of such leg and preferably below the table top. The detachable pedal-element is of lightweight non-bulky construction and is unencumbered by connecting wires, so that it may be easily removed from the table-leg and stored when not in use. Furthermore its operative position relative to the table is fixed, and consequently is easily found by the operator's foot. Still further, there is no danger of tipping it over.

In the accompanying drawings, Fig. 1 is a perspective view of a library table sewing machine outfit embodying the invention; the table being closed. Fig. 2 is a transverse vertical section through the table. Fig. 3 is a section on the line 3—3, Fig. 2. Fig. 4 is a vertical section through the lower end portion of the hollow leg of the table. Fig. 5 is a vertical section on the line 5—5, Fig. 4. Fig. 6 is a perspective view of the detachable pedal member. Fig. 7 is a disassembled perspective view of the pedal shaft, cam-shaft and cam-shaft bearing. Fig. 8 is a perspective view of the crank element provided on the controller rock-shaft. Fig. 9 is a transverse vertical section through a library table sewing machine outfit embodying a modification of the invention. Fig. 10 is a fragmentary bottom plan view, partly in horizontal section, of the parts shown in Fig. 9. Fig. 11 is a view on the line 11, 11, Fig. 9, with the sewing machine removed. Fig. 12 is a fragmentary view of the parts, similar to Fig. 9, but showing the connection to the sewing machine controller as broken. Fig. 13 is a bottom plan view of the guide for the shiftable connector element. Fig. 14 is a perspective view of the shiftable connector element; and Fig. 15 is a perspective view showing the shiftable

connector element in operative engagement with the controller rock-shaft.

Referring more particularly to Figs. 1 to 6, inclusive, 1 represents a sewing machine table having the top 2 and hinged cover leaves 3. The table includes the detachable legs 4, 4', end-walls 5, front wall 6 and rear wall 7; the space within such walls constituting a cavity below the table-top into which the sewing machine 8 is lowered through the aperture 9 in the table-top, in the usual manner, when not in use. The legs are removably secured by screws 4^a to the iron braces 4^b which join the ends of the table skirt members 5, 6 and 7. The sewing machine 8 is driven by an electric motor 10 preferably constructed and mounted substantially in accordance with the disclosure in the Diehl et al. Patent No. 1,488,234 of

March 25, 1924.

Fixedly mounted in the cavity of the table on an end wall 5 and independently of the sewing machine 8 is the motor controller 11 which is preferably constructed substantially in accordance with the disclosure of the pending application of D. H. Chason, Serial No. 750,734, filed Nov. 19, 1924. Such a controller comprises a compression type rheostat including a porcelain body 12 having wells filled with stacks 13 of carbon disks to which variable operative pressures are applied by means of the bridging bow-spring member 14 and its operating pull-rod 15. The pull-rod 15 is operated by the bellcrank-lever 16 fulcrumed at 17 and engaged by the cam-edge 18 on the arm 19 fixed to the controller rock-shaft 20 journaled in the bearing 21 and steadied at its outer end by the bearing bracket 22. A limited rocking movement of the shaft 20 thus serves to control the speed of the motor 10 by varying the electrical resistance of the motor circuit.

The table leg 4' is longitudinally channeled or hollow and has fitted to the horizontal aperture 23 in its lower end, the bearing sleeve 24 for the cam 25 and bearing 26 for the cam-shaft 27. The cam 25 is formed with a flat cam-face 28 upon which rests the lower end of the rod 29 extending upwardly and concealed within the hollow leg 4'. The rod 29 slides in the guiding bushings 4". The cam 25 is formed at one end with a tooth 30 adapted to be engaged by the tooth 31 of a detachable pedal. The pedal preferably comprises a pedal-arm 32 having at its free end a lateral extension 33 for engagement by the operator's foot. The pedal-arm 32 has fixed to its opposite end the enlarged cylindrical head 34 of a shaft-section 35 to which a tubular shaft-section 36 is fixed by means of the pin 37. The shaft-section 36 is adapted to be slipped over the cam-shaft 27 so that its tooth 31 will engage the tooth 30 of the cam-member 25.

To afford reaction pressure for the pedal

there is preferably provided a floor rest 38 having a foot 39 and bearing boss 40 journaled on the shaft 35. A spring 41 is coiled around the shaft-head 34 and is anchored at one end 42 to the arm 32. The other end 70 of the spring 41 bears against the ear 43 of the member 38. When the pedal 33 is depressed the cam-face 28 will lift the rod 29 which has fixed to its upper end portion a lateral arm 43, Fig. 2, extending into the 75 cavity of the table through the slot 44 in a guide-plate 45. A spring 46 surrounding the rod 29 within the table-leg and bearing downwardly upon the hub of the arm 43 insures retention of the rod 29 in engagement 80 with the face 28 of the lifting cam 25.

The arm 43 is tapped to receive a finely adjustable lifting screw 47 which impinges under an offset or crank-member 48 on the collar 49 fixed to the controller rock-shaft 20. 85 A lifting movement of the arm 43 and screw 47 will thus cause a rocking movement of the shaft 20 and a consequent reduction of the electrical resistance of the rheostat 12 and a speeding up of the sewing machine 90 motor. The screw 47 permits the range of motion of the controller rock-shaft 20 to be nicely co-ordinated with the range of motion of the rod 29.

When the outfit is not in use the sewing head 8 together with its motor 10 is lowered from its position in the table aperture 9 into the cavity of the table and the pedal member 32 is detached from the leg 4' and the table closed, whereupon the outfit has the appearance of a non-special or library table, as shown in Fig. 1.

The modification of the invention illustrated in Figs. 9 to 14, inclusive, is adapted for the operation of a portable type of sewing machine. In this case the table is formed with an aperture top 50 and supporting legs, one of which legs 51 is hollow. The table has a cavity below its top in which is mounted the stationary shelf 52. The sewing machine, which is of the portable type, comprises the usual sewing head 53; motor 54 and hollow wooden base member 55 of the usual carrying case. The base member 55 has mounted within it a controller 56 which is preferably of the same construction as the controller 12 and has an operating rock-shaft 57 to which is fixed a collar 58 formed with a tooth 59. The sewing machine and motor, together with the base 55 rest as a removable unitary assembly upon the shelf 52; the base 55 being received within the aperture 60 in the table-top 50 with the upper surface 61 of the base flush with the table-top.

Concealed within the hollow leg 51 is a rod 62, the lower end of which rests upon a cam-lifting device 63 of the same construction as the cam 25 and associated parts previously described. This cam device 63 is 120

- operated by a detachable pedal member 64 of the same construction as the detachable pedal 33 and associated parts previously described. The rod 62 also has fixed to its upper end-portion an arm 65 carrying an adjustable lifting screw 66 and is surrounded by a spring 67, the purpose of which is to insure retention of the rod 62 in engagement with its lifting cam 63.
- 10 Hinged at 68 on the bracket 69, is a lever 70 having an enlarged end 71 upon which rests the lower end of an inclined arm 72 fixed to the rocking and endwise movable shaft 73 which is journaled in the bracket 74; the screw 66 being in lifting engagement with the lever 70. The shaft 73 is projected into an aperture in the base 55 and over the controller rock-shaft 57 and is formed with coupling means in the form of an end shoulder 75, Fig. 15, which engages complementary coupling means in the form of a tooth 59 of the collar 58. The rod 62, when lifted, will swing the lever 70 upwardly and lift the arm 72, thus rocking the shaft 73 and the controller-shaft 57.
- When the outfit is not in use the shaft 73 may be withdrawn from the controller rock-shaft by means of the handle 76 and turned to carry its arm 72 clear of the lever 70 and the shank of the handle 76 into engagement with the retaining notch 77 in the bracket 74, as shown in Fig. 12; the withdrawal of the shaft 73 being effected against the pressure of the spring 78. In this position of the parts the end of the shaft 74 is clear of the base 55 so as not to interfere with the removal of the unitary portable sewing machine assembly from its position in the table.
- 15 The controller operating mechanism thus includes an element carried by the table and projectible into the sewing machine base for connection with the motor-controller, which element may be withdrawn to permit ready removal of the sewing machine from the table.
- The table may be shipped with the legs removed and readily re-assembled for use by one not possessed of special training or 20 mechanical skill, the mere act of attachment of the hollow leg 4' to the table correctly locates the screw 47 or the screw 66 relative to the respective coacting follower element 48 or 70.
- 25 Having thus set forth the nature of the invention, what I claim herein is:
1. An electric sewing machine outfit comprising a table having a table-top and a plurality of supporting legs free of connection with one another below their upper end-portions which adjoin the table-top, a sewing machine carried by said table, a motor associated with the sewing machine, a motor-controller connected to said motor, a controller operating connection extending 30 downwardly within and concealed by one of said legs, and a pedal detachably connected to said connection adjacent the lower end of said one of said legs, said pedal being free of connection to the remaining legs. 70
  2. An electric sewing machine outfit comprising a sewing table having a table-top and supporting legs, one of which legs is hollow, a sewing machine carried by said table-top, a motor associated with the sewing machine, and a motor speed-controller connected to said motor, a pedal connected to said hollow leg, and an operative connection between said pedal and controller housed within said hollow leg, said operative connection including an adjustment screw for coordinating the range of movement of the controller to that of the pedal. 75
  3. An electric sewing machine outfit comprising a sewing table having a table-top and supporting legs, one of which legs is hollow, a sewing machine carried by said table-top, a motor associated with the sewing machine, and a motor speed-controller connected to said motor, a pedal-shaft 80 mounted transversely of said hollow leg adjacent the lower end of the latter and free of connection with the remaining legs, a vertical rod concealed within said leg and connected at its lower end to be operated by said pedal-shaft, means operatively connecting the upper end of said rod to said speed-controller, and a pedal detachably connected to said pedal-shaft. 85
  4. An electric sewing machine outfit comprising a sewing table having a table-top and supporting legs, a sewing machine carried by said table-top, a motor associated with the sewing machine, and a motor speed-controller connected to said motor, a cam housed in one of said legs, a rod actuated by said cam, means operatively connecting said rod to said speed-controller, and a pedal connected to said cam. 90
  5. An electric sewing machine outfit comprising a sewing table having a table-top and supporting legs, a sewing machine carried by said table-top, a motor associated with the sewing machine, and a motor speed-controller connected to said motor, means for operating said motor speed-controller, and a pedal detachably connected to one of said legs and said means, said pedal including a floor rest, a pedal-shaft journaled in said floor rest, a pedal-arm carried by said shaft, and a reaction spring intermediate said floor rest and said pedal, arm and shaft. 95
  6. An electric sewing machine outfit comprising a sewing machine and driving motor, a table carrying said sewing machine and motor, said table having a top and being formed below its top with a cavity for reception of the machine when not in use, said table also including supporting legs, a motor speed-controller connected to said 100

motor and fixedly mounted in said table-cavity independently of the sewing machine, controller operating mechanism associated with said table including an element extending downwardly within one of said legs, and a pedal detachably connected to said element adjacent the lower end of said one of said legs.

7. An electric sewing machine outfit comprising a sewing machine and driving motor, a table carrying said sewing machine and motor, said table having a top and being formed below its top with a cavity for reception of the machine when not in use, said table also including supporting legs, a motor speed-controller fixedly mounted in said table-cavity independently of the sewing machine, a controller operating pedal detachably connected to one of said table-legs, and an operative connection between said pedal and controller in permanent operative relationship with said controller.

8. An electric sewing machine outfit comprising a sewing machine and driving motor, a table carrying said sewing machine and motor, said table having a top and being formed below its top with a cavity for reception of the machine when not in use, said table also including supporting legs, one of which is hollow, a motor speed-controller mounted in said table-cavity and including an operating rock-shaft and crank-arm, a controller operating pedal detachably connected to said hollow table-leg,

and an operative connection between said 25 pedal and controller concealed within said hollow leg, said connection including a vertically movable slide-rod, and a lifting arm secured to the upper end of said slide-rod and adapted to engage under and lift said 40 crank-arm to rock the controller-shaft.

9. An electric sewing machine outfit comprising a table including a table-top and detachable supporting legs, a sewing machine carried by said table, a motor associated with 45 the sewing machine, a motor-controller carried by said table, a pedal operated member mounted in one of said detachable legs, and means operatively connecting said pedal-operated member and said controller, said 50 means including coacting elements carried respectively by the table and said one of said legs and adapted to be cooperatively related by the act of attachment of such leg to the table.

10. An electric sewing machine outfit comprising a table including a table-top and supporting legs, a sewing machine carried by said table, a motor associated with said sewing machine, a motor-controller mounted 60 under said top, means housed in one of said legs for actuating said controller, and a pedal extending into said leg for operating said means.

In testimony whereof, I have signed my 65 name to this specification.

FREDERICK DIEHL.
